CLAIM

The ornamental design for a pistol-style spray head, as shown and described.

DESCRIPTION

FIG. 1 is a top perspective view of the pistol-style spray head showing my new design, with the safety in the safe position; FIG. 2 is a left side elevational view of FIG. 1; FIG. 3 is a front elevational view of FIG. 1; FIG. 4 is a right side elevational view of FIG. 1; FIG. 5 is a rear view of FIG. 1; FIG. 6 is top plan view of FIG. 1; FIG. 7 is a bottom plan view of FIG. 1; FIG. 8 is a top perspective view of the pistol-style spray head showing my new design, with the safety in the fire position; FIG. 9 is a left side elevational view of FIG. 8; FIG. 10 is a front elevational view of FIG. 8; FIG. 11 is a right side elevational view of FIG. 8; FIG. 12 is a rear view of FIG. 8; FIG. 13 is top plan view of FIG. 8; and, FIG. 14 is a bottom plan view of FIG. 8. The dot-dash-dot broken lines illustrating a bottle depict environment and form no part of the claimed design. The interior dash-dash broken lines in the underside of the pistol-style spray head in FIGS. 7 and 14 depict the boundaries of the claim and form no part thereof. All other broken

(Continued)

lines depict portions of the pistol-style spray head that form no part of the claimed design.

1 Claim, 6 Drawing Sheets
